CHAISE LONGUE

Hugo Perlesz, Chicago, and Charles F. Pearce, Jr.,
Glencoe, Ill., assignors to Burton-Dixie Corporation,
Chicago, Ill., a corporation of Delaware

Application May 15, 1933, Serial No. 671,042

4 Claims. (Cl. 155—49)

This invention relates to furniture in general, and has been illustrated as embodied in a chaise longue of a type which might be converted to a bed. The forms of the invention illustrated 5 comprise a metallic frame chaise longue having a seat portion adjustable as to inclination, a back portion also adjustable as to inclination, and a foot or leg rest which may also be adjustable as to inclination. The back portion 10 may be lowered to a level position to form a bed and in so doing it automatically levels the seat portion. This automatic leveling feature is one of the important aspects of the invention, as it may be used in a wide variety of furniture. It 15 involves the pivoting of the back to the legs in such manner that as the upper end of the back is swung down, the lower end of the back structure raises the seat to the proper level. The entire chaise longue with the arms removed may be 20 folded to a compact position in which it is readily packed for shipment or carrying in an automobile. According to the preferred form of the invention, the springs are formed of a continuous fabric for the entire back seat, with the result 25 that when the back is raised the connecting zone between the back and the seat is smoothly and gently curved. When preferred, however, the back and the seat spring fabrics may be separated, although in that case it is preferred that 30 each be terminated with a flexible spring supported band for the sake of comfort when used as a bed.

It is the object of the invention to provide a chaise longue having the various features above 35 described, particularly one that is convertible to form a bed. It is a further object to provide such a piece of furniture which can be manufactured economically and cheaply, and which nevertheless will be thoroughly reliable and comfortable.

In the drawings, which illustrate an embodiment of the device, and wherein like reference characters are used to designate like parts,

Figure 1 is a perspective view of the article in 45 its chaise longue position;

Figure 2 is a side elevation of the structure shown in Figure 1 with the flounce removed for the sake of clarity;

Figure 3 is a side elevation of the structure 50 of Figures 1 and 2, but shown in the position of a bed;

Figure 4 is a rear view of a slight modification of the structure as shown in Figure 2, but being shown in the same position as Figure 2;

55 Figure 5 is a perspective view of the structure

of Figure 4 folded up for travel or shipment, the arms and mattress being omitted.

Although my invention may take many forms, only one form, with a slight modification thereof, has been chosen for illustration. Except as to their points of difference, the two modifications will be described together as if they were the same. The structure includes the seat frame 10, the back frame 12 and the extension frame 14. To the seat frame 10 are secured the 10 seat front legs 16 which may be braced to each other by a cross bar 17 and which are normally held in a rigid position with respect to the frame 10, by the braces 18 pivoted to frame 10 and hooked over pins 19. To the frame 12 are pivoted floating legs 20 by pivotal pins 21. The legs 20 are normally braced with respect to the seat portion by the braces 22 which extend between the pivots 24 on the legs and the pivots 26 on the seat portion. The legs 20 are braced 15 with respect to each other by an angle brace 27 and a cross bar 29. The back frame 12 has secured thereto a connecting plate 28 which is pivoted at 30 to a similar connecting plate 32 which is rigidly secured to the seat frame 10. 25 The back frame 12 is held at any of a variety of upright angles by detachable arms 34 which are secured to the seat frame as by thumb screws 36 and to the back frame by a headed pin 38 on said frame in cooperation with a slot 40 having notches 41, and an enlarged hole 42 which may be pressed over the head of the pin 38. If desired, the slot 40 may also be provided with an elongation which will permit the movement 30 of the back to the bed position. For this movement, however, the arm may be completely removed from the pin 38 if desired, and in fact from the entire structure. So that the arm may be swung out of the way, as shown in Figure 3, the upright and horizontal portions may be pivoted by a pin 43. In this case, a brace 44 is pivoted at 45 to the horizontal part of the arm and removably secured as at 46 to the upright. 40

The back frame 12 pivots about the pins 21, thereby raising the pivots 30 which in turn raise 45 the rear end of the seat frame 10 until the seat frame 10 and back frame 12 are both horizontally positioned, and at the same level, as shown in Figure 3. It will be observed that in the course of the change, the leg 20 has considerably 50 changed its position; to facilitate this, the casters or rollers 48 are provided, which also make the chaise longue as a whole more easily moved. The particular construction shown, involving the folding leg 20, simplifies the automatic leveling 55

feature of the invention. Not only does it permit the necessary movement between the two frames 10 and 12, but it also increases the leveling function, since, in the process of straightening up from the position shown in Figure 2 to the position shown in Figure 3, it raises the main pivotal support pin 21.

The extension frame 14 is provided with legs 50 which are pivoted as at 52 and which are preferably provided with a small coil spring 54 which is so arranged as to hold the legs either in the position shown in full lines in Figure 2, or in the position shown in dotted lines in Figure 2. The legs 50 will hold the extension 14 in a horizontal position to serve either as the foot of the bed or as the leg rest for the chaise longue. If the legs 50 are collapsed, as indicated in dotted lines in Figure 2, the frame 14 may rest directly on the floor to provide an alternative chaise longue or chair position. The back 12 is provided with legs 56 similar to legs 50, and likewise retained in either position by coil spring 58. It may be mentioned that by careful selection and mounting of the coil spring 58 a balance may be obtained which will keep the legs 56 in their collapsed position when the back is nearly upright for one of the sitting positions, but which will permit the legs 56 to drop as the back is lowered nearly to the horizontal position, at which time the collapsed legs will exert a maximum turning torque about their pivots. All of the legs 16, 50 and 56 and also the extension 14 may be provided with floor-protecting cushions or the like 60.

The extension 14 may be terminated at its seat end with an angle bar 62, to hold a spring fabric 64 independent of the remainder of the spring fabric. This extension member may be either hinged, as by the hinges 66 to an angle bar 68 forming the lower end of the seat frame 10, or may be detachable from the seat frame, in which case provision will preferably be made for its support below the frame when not in use.

It is preferred that the seat 10 and back 12 be provided with a single spring fabric 10, and that this have considerable resiliency both longitudinally and transversely, so that when the structure is on the chaise longue position shown in Figures 1 and 2, the central portion of this fabric will be drawn into a smoothly and gently rounded position, instead of closely following the angle between the frames. This longitudinal and transverse resiliency may be secured by the use of coil springs 72. It is of course important that there be no rigid members in the frames at this point, since such members would make the structure uncomfortable when used as a bed.

Such rigid members may be avoided in another way, however, as shown in the modified structure of Figure 4. In this structure, each of the spring fabrics of the seat and of the back is terminated 60 adjacent the other by a flexible metal band 74. (Only one of these is visible in Figure 4.) These metal bands are supported by coil spring 16, so as to be fully yieldable. If desired, the metal band 65 of the back section may be elongated to the metal band of the seat section by coil springs, thus making a continuous spring fabric for the two sections. A cushion may be provided either in one piece, as shown, or in more than one piece, 70 and it may be provided with a pocket-like hanger 78 made to fit over the end of the back frame 12. There may also be provided suitable tie cords 80, if desired.

The arms may be provided with top members 75 82 having large flat surfaces to serve not only for

arm rests, but for holding a glass, sewing basket, or the like. If these tops are metallic they may be folded under along all edges to present a smoother edge.

In Figure 5 is illustrated the structure folded up (with the arms removed). Little explanation is needed except to say that after the legs have all been folded to their collapsed positions, the braces 18 and 22, having been detached from the legs, the extension frame 14 may be folded up over and onto the frame 10, whereupon the back frame 12 may be folded over the extension frame 14. The structure is then in a convenient form either for shipping or for transport by automobile, either inside of it or on the running board. 15

Although the chaise longue bed has been illustrated in a size suitable for one person, it should be obvious that it may be made wider so that it will be suitable for two or more persons, and so that when the back is lowered it will make a full 20 size double bed.

It is to be understood that many other embodiments of the invention, including some in improved form, will be apparent, and in the course of time more will be devised by those skilled in the art. It is not desired that this invention be limited to the details described, for its scope includes all such forms or improvements as come within the spirit of the following claims, construed as broadly as the prior art will permit. 30

What is claimed is:

1. A chaise longue having in combination a seat, a back pivotally connected to said seat and normally inclined upwardly therefrom, means supporting said seat normally in position slightly inclined from the horizontal, including a leg pivotally connected to the back rearwardly and upwardly of the point at which the back is pivoted to the seat and inclined rearwardly and downwardly therefrom, the lower end of said leg being provided with means by which the leg is freely movable upon the floor or other support, and a link pivotally joined at one end to said leg and having its other end pivotally connected to the seat forwardly of the pivot connecting the seat and the back, whereby lowering of the back to a substantially horizontal position raises the seat to a substantially horizontal position. 35

2. A chaise longue having in combination a seat, a back pivotally connected to said seat and normally inclined upwardly therefrom, means supporting said seat normally in position slightly inclined from the horizontal, including a leg pivotally connected to the back rearwardly of the point at which the back is pivoted to the seat and 50 inclined rearwardly and downwardly therefrom, the lower end of said leg being provided with means by which the leg is freely movable upon the floor or other support, and a link pivotally joined at one end to said leg and having its other end pivotally connected to the seat forwardly of the pivot connecting the seat and the back, whereby lowering of the back to a substantially horizontal position raises the seat to a substantially horizontal position. 55

3. A chaise longue having in combination two frame members, one forming a seat and the other a back, said back being pivotally connected to said seat and normally inclined upwardly therefrom, means supporting said seat normally in position slightly inclined from the horizontal, including a leg pivotally connected to one frame member at a point spaced from the point at which the back is pivoted to the seat and inclined rear- 70

wardly and downwardly therefrom, the lower end of said leg being provided with means by which the leg is freely movable upon the floor or other support, and a link pivotally joined at one end to said leg and having its other end pivotally connected to the other frame member at a point spaced in substantially the opposite direction from the pivot connecting the seat and the back, whereby lowering of the back to a substantially horizontal position shifts said leg to a more nearly vertical position and thereby raises said seat toward the horizontal position.

4. A chaise longue having in combination two frame members, one forming a seat and the other a back, said back being pivotally connected to said seat and normally inclined upwardly therefrom, means supporting said seat normally in position slightly inclined from the horizontal, including a leg pivotally connected to one frame member at a point spaced from the point at which the back is pivoted to the seat and inclined rearwardly and downwardly therefrom, the lower end of said leg being provided with means by which the leg is

freely movable upon the floor or other support, a link pivotally joined at one end to said leg and having its other end pivotally connected to the other frame member at a point spaced in substantially the opposite direction from the pivot connecting the seat and the back, whereby lowering of the back to a substantially horizontal position shifts said leg to a more nearly vertical position and thereby raises said seat toward the horizontal position, and an arm structure for normally securing said back in an inclined position; said arm structure being pivotably connected to said seat and said back at points remote from the point where said back is pivoted to said seat, and including two members which are pivoted together and means normally holding said two members in a given angular relation to one another but releasable to permit said member to pivot with respect to one another toward an aligned position when said back is lowered.
